UNITED STATES PATENT OFFICE.

LEWIS DOUGLAS YOUNG, OF PROVIDENCE, RHODE ISLAND, ASSIGNOR TO YOUNG BROTHERS, OF PROVIDENCE, RHODE ISLAND.

DISPLAY BOX.

Application filed February 9, 1924. Serial No. 691,838.

To all whom it may concern:

Be it known that I, LEWIS D. YOUNG, a citizen of the United States, residing at Providence, in the county of Providence and State of Rhode Island, have invented new and useful Improvements in Display Boxes, of which the following is a specification.

This invention relates to certain new and useful improvements in display boxes and the primary object of same is to provide novel means of a simple and inexpensive character for supporting the box at an incline so as to more effectively display its contents.

A further object of the invention is to provide box supporting means which can be easily and quickly applied to and removed from the box and housed therein.

20 The invention still further aims to provide supporting means which enables the customary appearance of the box to be preserved.

Other objects will be later set forth and manifested in the course of the following description.

In the drawings:

Figure 1, is a side elevation of the preferred form of the invention;

30 Figure 2, is a section on line 2—2 of Figure 1;

Figure 3, is a section on line 3—3 of Figure 1;

Figure 4 is a perspective view of one of the supports;

Figure 5 is a top plan view;

Figure 6 is a side elevation of a modified form of the invention;

40 Figure 7 is a section on line 7—7 of Figure 6, and

Figure 8 is a section on line 8—8 of Figure 6.

In accordance with the invention, a box is employed having a bottom 20, sides 21 and ends 22, transverse strips 23 being secured adjacent to the ends in spaced relation thereto to form end slots.

50 The supports are preferably formed of pasteboard and include bodies 24 the lower or bottom edges 25 of which are formed to flatly seat on a supporting surface. The upper end portions of the supports are formed with necks 26 of reduced width, providing shoulders 27 which engages the sides 21 and restrict movement of the necks

through the slots and afford seats for the box. The supports and shoulders are formed so that the box will be held at an incline with its lower longitudinal side disposed above the supporting surface. 60

From the above it will be apparent that two supports may be easily and quickly applied to and removed from the box ends, and after removal may be housed within the box to facilitate shipping or storage. 65

Obviously the supports may be variously configured so as to present an attractive and ornamental appearance.

In accordance with a modified form of invention, a box is employed with a bottom 70 as 1, ends 2 and 3 and sides 4, as usual. At the end 2 of the box, a transverse strip 5 is suitably secured so as to lie spaced from the end. The support includes a preferably pasteboard member 6, the bottom of 75 which is formed to seat on a supporting surface, while the upper end thereof has an attenuated neck portion 7 of a width to freely pass through the space between strip 5 and end 2 of the box. The shoulders 8 80 resultant from the reduction in width of the neck portion 7, abut the sides 4 of the box and restrict movement of the neck through the slot or space between strip 5 and end 2 of the box. The upper end of the neck is demarcated by a line of weakening 9, the portion beyond the line forming a head 10 85 which may bear advertising or other matter as desired, the line of weakening permitting the head to be bent so as to lie at an incline, 90 as shown in Figure 1.

From the above it will be apparent that the line of weakening or fold 9, permits the head 10 to be folded so as to allow the support to be housed within the box in order to facilitate shipping, or storage. In applying the support to the box, it is merely necessary to pass the head and neck through the slot between end 2 and strip 5 until the shoulders 8 engages sides 2, following which the head is bent to lie at an incline. 100

The body 6 may be shaped as desired to enhance its appearance so as to render same attractive.

Having thus described my invention, what 105 I claim as new and desire to secure by Letters Patent is:—

1. In combination with a box having a slot extending along each end thereof, a pair of supports having bottoms formed 110

to seat on a supporting surface and having tops formed to be inserted through said slots with shoulders at the bases of the tops to engage the box bottom, the shoulders 5 being spaced above the bottoms of the supports to hold the entire box spaced above a supporting surface.

2. In a display box, a box having a transverse strip secured thereto spaced from a 10 wall of the box to form a slot, and a support for the box separate therefrom to hold same at an incline having a surface engaging portion and a neck with shoulders at the neck base, the neck being insertible in the slot and 15 the shoulders being engageable with the box.

3. In a display box, a box having a pair of slots at its opposed ends, and a pair of independent supports formed separate from the box and insertible at their tops in the 20 respective slots so as to be each held in operative position by the slot and having parts at their tops to engage the box bottom to hold the latter at an incline, said supports being removable from the slots so as to be 25 stored in the box.

4. In a display box, a box having a pair of slots extending across its respective ends, and a pair of supports having bases formed 30 to seat at their bottoms on a supporting surface, necks at their tops insertible in the slots and having shoulders at the bases of the necks to engage the box, the supports being independent of the box, and the necks and 35 slots being of such length so as to hold the supports in operative position.

5. In a display box, a box having a strip at each end thereof extending thereacross to form slots in conjunction with the ends, and supports for the box having parts insertible in the slots. 40

6. In a display box, a box having a strip at each end thereof extending thereacross to form slots in conjunction with the ends, and supports for the box having parts insertible in the slots and having shoulders 45 to restrict movement of the supports in the slots.

7. In a display box, a box having a strip at each end thereof extending thereacross to form slots in conjunction with the ends, 50 supports for the box having parts insertible in the slots and means to restrict movement of the supports in the slots.

8. In a display box, a body having a slot at each end thereof, and a support for each 55 end of the body independent of and removable therefrom, each support having a bottom part to seat on a supporting surface and each having a part at the top thereof to engage in the respective slots, the slots and 60 top parts of the supports being of such length so as to hold the supports in operative position.

In testimony whereof I have signed my name to this specification in the presence of 65 two subscribing witnesses.

LEWIS DOUGLAS YOUNG.
